UNITED STATES PATENT OFFICE.

NATHAN I. BERGER, OF NEW YORK, N. Y.

DESIGN FOR A PLATE FOR LIGHTING FIXTURES.

Application filed July 27, 1927. Serial No. 22,890. Term of patent 3½ years.

To all whom it may concern:

Be it known that I, NATHAN I. BERGER, a citizen of the United States, and a resident of the borough of Manhattan, city, county, and State of New York, whose post-office address is 1440 Broadway, in the borough of Manhattan, city, county, and State of New York, have invented a new, original, and ornamental Design for a Plate for Lighting Fixtures, of which the following is a speci-

fication, reference being had to the accompanying drawing, forming part thereof.

Figure 1 is a plan view of the plate for lighting fixtures, showing my new design, and Figure 2 is a side view thereof.

I claim:

The ornamental design for a plate for lighting fixtures, as shown.

NATHAN I. BERGER.
